FOREIGN PATENT DOCUMENTS

DE WO 02094122 A2 * 11/2002 ..... A61D 7/04

Primary Examiner — Susan Moon Lee(74) *Attorney, Agent, or Firm* — Smith Moore Leatherwood LLP; Thomas W. Epting(57) **CLAIM**

The ornamental design for an equine mask, as shown and described.

DESCRIPTION

FIG. 1 is a perspective view of an embodiment of an equine mask showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

Broken lines and unshaded portions contained within broken lines are not claimed.

1 Claim, 7 Drawing Sheets---
